UNITED STATES PATENT OFFICE.

JULIUS F. GOETZ, OF HARTFORD, WISCONSIN.

VAPORIZER AND AIR-SUPPLY DEVICE.

Application filed February 10, 1919. Serial No. 276,107.

To all whom it may concern:

Be it known that I, JULIUS F. GOETZ, a citizen of the United States, and resident of Hartford, in the county of Washington and 5 State of Wisconsin, have invented new and useful Improvements in Vaporizer and Air-Supply Devices, of which the following is a description, reference being had to the accompanying drawings which are a part of 10 this specification.

This invention relates to improvements in vaporizer and air supply devices.

In internal combustion engines more particularly adapted for automobile use, it has 15 been found that the engines run to better advantage under some atmospheric conditions than others and that this result is produced more or less by the varying conditions of humidity of the air. Many attempts have 20 been made to provide means for meeting the different atmospheric changes, but heretofore the means do not permit the convenient control of the devices.

It is one of the objects of the present 25 invention to provide a combined vaporizer and air supply device which will supply vapor and hot or cold air to the carbureter of the engine as required to supply the proper mixture under any atmospheric condition.

A further object of the invention is to 30 provide a vaporizer and air supply device in which the controls of the vapor and hot and cold air are combined in a manner to be conveniently operated from the dash or other 35 point desired of the automobile.

A further object of the invention is to provide a vaporizer and air supply device which may be connected to the valve of the carbureter to control the combined flow of vapor 40 and air thereto.

A further object of the invention is to provide a vaporizer and air control device 45 which may be easily connected to a carbureter of an ordinary engine in a manner to efficiently mix the vapor and air with the carbureter explosive fluid.

A further object of the invention is to 50 provide a vaporizer and hot and cold air supply device in which any desired combustible fluid mixture may be obtained to suit different atmospheric conditions.

A further object of the invention is to provide a vaporizer and air supply device

which is of simple construction, is strong 55 and durable, and is well adapted for the purpose desired.

With the above and other objects in view the invention consists of an improved vaporizer and air supply device and its parts 60 and combinations as set forth in the claims, and all equivalents thereof.

In the accompanying drawings in which the same reference characters indicate the 65 same parts in all of the views:

Fig. 1 is a side view, partly in section, of the improved vaporizer and air supply device shown connected to a portion of a radiator or a carbureter, the control portions of the device shown as mounted on the dash 70 of an automobile;

Fig. 2 is a top view thereof, parts being shown in section, the view also showing an engine to which parts are connected;

Fig. 3 is a face view of the controlling 75 members of the device;

Fig. 4 is a vertical sectional detail view of the valves controlling the air and vapor supply taken on line 4—4 of Fig. 1;

Fig. 5 is a similar view taken on line 80 5—5 of Fig. 1;

Fig. 6 is a vertical sectional view taken on line 6—6 of Fig. 1 of the main valve controlling the supply of vapor and air to the carbureter;

Fig. 7 is a detail sectional view of the air heating means;

Fig. 8 is a sectional detail view on a larger scale of the means for supplying the vapor and air to the carbureter;

Fig. 9 is a part sectional view of a modified form of the part shown in Fig. 8; and

Fig. 10 is a vertical sectional detail view, on a larger scale, of the part shown in Fig. 9.

Referring to the drawings, the numeral 12 95 indicates an internal combustion engine, 13 the carbureter, 14 the radiator and 15 a portion of the dash and instrument board of an automobile. The improved vaporizer and air supply device is connected to the 100 parts mentioned and comprises mainly the plural valve 16, the controlling main valve 17 and the plural valve controllers 18.

The plural valve 16 consists of a valve member 19 having four conical plug valves 105 20, 21, 22 and 23 mounted therein and rotatable to have their respective ports intersect and register with ports 24, 25, 26 and 27,

respectively extending radially from a center mixing chamber 28 formed in the valve member to the outer portions of said valve member. The plug valve 20 controls the supply of hot air to the mixing chamber 28, the valve 21 controls the supply of vapor thereto, and the valve 22 controls the supply of cold air to said chamber 28. Valve 23 controls the flow of air and vapor from the chamber 28 to the carbureter 13.

The plug valves are respectively connected to preferably flexible steel wire or rods 29 which extend forwardly and at their forward ends are clamped in the inner ends of controlling members or handles 30 which are journaled in a controller plate 31. The controlling members are formed with indicating pointed portions 30' and the controller plate is provided with indicating segmental scales 32 to indicate the adjustment of the opening of each valve. Coiled springs 33 surrounding the controlling members or handles 30 and interposed between portions of the controller plates and portions of the controlling members maintain said controlling members in adjusted position.

The controller plate 31 is preferably mounted on the instrument board of an automobile and as the controlling handles carried by said plate are preferably in horizontal alinement with each other and out of alinement with the plug valves with which they are respectively connected, the steel rod connections 29 provide the necessary flexibility to permit the easy turning of the plug valves.

A tube 34 coupled to the hot air port portion 24 of the valve member 19 extends to a position adjacent the exhaust pipe 35 and is connected to a tubular heater member 36 which partly surrounds and is spaced from the exhaust pipe. The air in the space between the heater member and the exhaust pipe is heated by the exhaust pipe and is drawn through the tube 34 to the valve mixing chamber 28.

A tube 37 coupled to the vapor port portion 25 of the valve member 19 extends to the radiator 14 of the automobile and is provided with an extension 37' which extends into the upper portion of the radiator and is curved upwardly and its upper end terminates at a point in the upper portion 38 of the filling opening of said radiator. Openings 39 formed in said upper pipe end permit the moist vapor in the upper portion of the radiator to enter the tube and be drawn to the mixing chamber 28 of the valve member 16.

The cold air port portion 26 of the valve member 16 is also provided with a coupled tube 40 which extends to any convenient point and is fastened to the dash board by a securing member 41. The terminating end of this tube is provided with a screen cover

42 which prevents dust or other foreign matter being drawn into the tube and the valve mixing chamber 28, with the cold air.

A tube 43 connected to the outlet port portion 27 extends and is connected to the carbureter 13 by an annular member 44 which is interposed between the carbureter and the engine. The annular member is shaped to correspond to the shape of the carbureter connecting flange to permit the same bolts 75 45 to connect the parts together.

The annular member 44 is formed with an annular space or chamber 44^a having an inner wall of perforated or screen material 46 to efficiently mix the vapor or hot or cold air 80 with the combustible mixture passing through the annular member from the carbureter to the engine. A screen or perforated disk 47 may also be used if desired to more completely atomize the particles of 85 gasoline or other fluid which might be carried by the air.

The shut off valve 17 before mentioned is connected in circuit with or intersects the flow of air or vapor through the tube 43 and the controlling plug member 17' of this valve has a yielding connection 48 with the throttle valve 49 of the carbureter 13 so that when said throttle valve is controlled in the ordinary way from the steering head the supply of vapor or hot or cold air from the device will be automatically controlled independently of the proportionate controls of the vapor or hot and cold air.

In the modified form shown in Fig. 9 the tube 43 is connected directly to carbureter and is provided with a perforated and screened extension 50 which extends into the carbureter in the path of travel of the combustible mixture and supplies the hot or cold air or vapor thereto.

From the foregoing description, it will be seen that varying amounts of vapor or hot or cold air may be easily mixed and controlled and supplied to the combustible fluid fed to the engine to suit varying atmospheric conditions and thereby provide an efficient mixture at all times.

What I claim as my invention is:

1. The combination with an engine having a carbureter, a radiator and an air heater, of a valve structure comprising a mixing chamber provided with two inlet ports and an outlet port, pipes connecting said inlet ports with the radiator and the air heater, respectively, a pipe connecting said outlet port with the carbureter, a valve in said last mentioned pipe, means operatively connecting said valve with the throttle valve of the carbureter, valves controlling said inlet ports, and means operable from a remote point for controlling independently said last mentioned valves, whereby the relative proportions of air and vapor admitted to said mixing chamber may be varied at 115 120 125 130

will and the mixture delivered to the carbureter controlled simultaneously with the movement of the carbureter throttle valve.

2. The combination with an engine having a carbureter, a radiator and an air heater, of a valve structure comprising a mixing chamber provided with three inlet ports and an outlet port, pipes connecting said inlet ports with the radiator, air heater and a source of cold air supply, respectively, a pipe connecting said outlet port with the carbureter, a valve in said last mentioned pipe, means operatively connecting said valve with the

throttle valve of the carbureter, valves controlling said inlet ports, and means operable from a remote point for controlling independently said last mentioned valves, whereby the relative proportions of warm air, cold air and vapor admitted to said mixing chamber may be varied at will and the mixture delivered to the carbureter controlled simultaneously with the movement of the carbureter throttle valve.

In testimony whereof, I affix my signature.

JULIUS F. GOETZ.
